UNITED STATES PATENT OFFICE.

THEODORE W. FOSTER, OF PROVIDENCE, RHODE ISLAND.

DESIGN FOR A MIRROR OR SIMILAR ARTICLE.

41,356.

Specification for Design.

Patented May 2, 1911.

Application filed February 17, 1911. Serial No. 609,264. Term of patent 7 years.

To all whom it may concern:

Be it known that I, THEODORE W. FOSTER, a citizen of the United States, residing at Providence, in the county of Providence and State of Rhode Island, have invented a new, original, and ornamental Design for a Mirror or Similar Article, reference being had to the accompanying drawing.

The figure in the drawing is a plan view of the front of a mirror, showing my design.

I claim—

The ornamental design for a mirror or similar article, as shown.

THEODORE W. FOSTER.

Witnesses:

ADA E. HAGERTY,
J. A. MILLER.
